US00D960636S

(12) **United States Design Patent** (10) **Patent No.:** **US D960,636 S**
McConnell et al. (45) **Date of Patent:** **** Aug. 16, 2022**

(54) **POWERED WHISK**

(71) Applicant: **WHIRLPOOL CORPORATION**,
Benton Harbor, MI (US)

(72) Inventors: **John W. McConnell**, St. Joseph, MI
(US); **Yifan Wang**, St. Joseph, MI
(US); **Wenkai Wu**, Aurora, IL (US)

(73) Assignee: **Whirlpool Corporation**, Benton
Harbor, MI (US)

(**) Term: **15 Years**

(21) Appl. No.: **29/815,660**

(22) Filed: **Nov. 16, 2021**

Related U.S. Application Data

(63) Continuation of application No. 29/795,502, filed on Jun. 18, 2021, now Pat. No. Des. 939,268, which is a continuation of application No. 29/764,246, filed on Dec. 29, 2020, now Pat. No. Des. 925,272, which is a continuation of application No. 29/741,533, filed on Jul. 14, 2020, now Pat. No. Des. 909,119, which is a continuation of application No. 29/682,096, filed on Mar. 1, 2019, now Pat. No. Des. 891,855.

(57) **CLAIM**

The ornamental design for a powered whisk, as shown and described.

DESCRIPTION

FIG. 1 is a front-perspective view of a powered whisk according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

1 Claim, 4 Drawing Sheets
